CLAIM

The ornamental design for a speaker grill with graduated hole sizing over a transition area for a media device, as shown and described.

DESCRIPTION

FIG. 1 is a perspective view, which includes a view of an enlarged portion for visibility, of a speaker grill with graduated hole sizing over a transition area for a media device, according to a first embodiment of the invention.

FIG. 2 is another perspective view of the first embodiment. FIG. 3 is a top view, which includes a view of an enlarged portion for visibility, of the first embodiment.

FIG. 4 is a bottom view of the first embodiment.

FIG. 5 is a first side view of the first embodiment.

FIG. 6 is a second side view of the first embodiment. FIG. 7 is a front view of the first embodiment. FIG. 8 is a back view of the first embodiment. FIG. 9 is a perspective view, which includes a view of an enlarged portion for visibility, of a speaker grill with graduated hole sizing over a transition area for a media device, according to a second embodiment of the invention. FIG. 10 is another perspective view of the second embodiment. FIG. 11 is a top view, which includes a view of an enlarged portion for visibility, of the second embodiment. FIG. 12 is a bottom view of the second embodiment. FIG. 13 is a first side view of the second embodiment. FIG. 14 is a second side view of the second embodiment. FIG. 15 is a front view of the second embodiment. FIG. 16 is a back view of the second embodiment. FIG. 17 is a perspective view of a speaker grill with graduated hole sizing over a transition area for a media device as illustrated further in FIG. 23, according to a third embodiment of the invention. FIG. 18 is another perspective view of the third embodiment. FIG. 19 is a top view, which includes a view of an enlarged portion for visibility, of the third embodiment. FIG. 20 is a bottom view of the third embodiment. FIG. 21 is a first side view of the third embodiment. FIG. 22 is a second side view of the third embodiment. FIG. 23 is a front view, which includes a view of an enlarged portion for visibility, of the third embodiment. FIG. 24 is a back view of the third embodiment. FIG. 25 is a perspective view of a speaker grill with graduated hole sizing over a transition area for a media device, according to a third embodiment of the invention. FIG. 26 is another perspective view of the third embodiment. FIG. 27 is a top view, which includes a view of an enlarged portion for visibility, of the third embodiment. FIG. 28 is a bottom view of the third embodiment. FIG. 29 is a first side view of the third embodiment. FIG. 30 is a second side view of the third embodiment. FIG. 31 is a front view, which includes a view of an enlarged portion for visibility, of a fourth embodiment; and, FIG. 32 is a back view of the fourth embodiment.

The dot-dash broken lines highlight portions of the speaker grill that are shown in an enlarged view and form no part of the claimed design.

The dot-dot broken lines are for illustrative purposes only, to distinguish between sections of the transition area that have holes of the same size, and form no part of the claimed design.

The features shown in dash-dot broken lines are for illustrative purposes only and do not form any part of the claimed design.
